VENTILATING APPARATUS

Allston Sargent, Bronxville, N. Y., assignor to
 Campbell Metal Window Corporation, New
 York, N. Y., a corporation of Maryland

Application July 11, 1932, Serial No. 621,865

4 Claims. (Cl. 62—129)

My invention relates to new and useful improvements in ventilating apparatus of the type to be installed in a room of a building or the like, and refers more particularly to an apparatus for cooling the air supplied to the room.

An object of my invention is to provide an apparatus in which the air is cooled by a refrigerating system.

Another object is to provide means for cooling the refrigerant condenser.

Another object is to provide a condenser cooling means which may be employed to withdraw air from the room.

The invention consists in the improved construction and combination of parts, to be more fully described hereinafter, and the novelty of which will be particularly pointed out and distinctly claimed.

In the accompanying drawings, to be taken as a part of this specification, I have fully and clearly illustrated two embodiments of my invention, in which drawings—

Figure 1 is a view in front elevation of an apparatus embodying my invention;

Fig. 2 is an enlarged view in section on the line 2—2 of Fig. 1;

Fig. 3 is a top plan view of the apparatus shown in Fig. 1;

Fig. 4 is an enlarged view in section on the line 4—4 of Fig. 1 and showing one embodiment of my invention;

Fig. 5 is an enlarged view in section of another embodiment of my invention, taken on the line 5—5 of Fig. 6, and

Fig. 6 is a view in section on a reduced scale taken on the line 6—6 of Fig. 5.

Referring to the drawings by characters of reference, 1 designates, generally, a floor of a room or other compartment in a building, having a wall 2 in which are window openings 3, 4 closed by windows 5, 6, respectively. Positioned within the room and supported by the floor, there are cabinets 7, 8 set substantially against the wall and preferably substantially beneath and in front of the windows 5, 6, respectively.

The cabinet 7 contains an air conditioning and ventilating apparatus, and is preferably substantially of the form and internal construction shown by Patent No. 1,949,379, granted February 27, 1934, on my copending application. For the purposes of the invention disclosed by this application it is unnecessary to illustrate and describe various special features of construction and arrangement of the cabinet 7 which are fully disclosed in said copending application, but it is

to be noted that the cabinet is divided by a partition including an upper portion 7' and an offset lower portion 7'' into two compartments or sections. The section of the cabinet 7 at the right of said partition is employed in the recirculation and cooling of room air, and may conveniently be designated as a cooling section, and the section at the left of the partition is employed in the introduction of external air into the room and may be designated as a fresh air section. The cooling section of the cabinet 7 is shown generally in vertical section in Fig. 2. The cooling section of the cabinet 7 contains a fan or blower 9 which may receive air through a cabinet inlet 10, and which discharges the in-drawn air upwardly through an outlet opening 11 in the top wall of the cabinet 7. Also within the cooling section of the cabinet there is a cooling unit or element 12 supported in any suitable manner in the path of the air discharged by the fan, so that the air will pass in intimate heat exchange relation thereto and be efficiently cooled in its passage through the cooling section of the cabinet. Such description as is required herein of the fresh air section of the cabinet 7 is found in a later portion of this specification.

Referring to Figs. 1, 3, and 4, the cabinet 8 is preferably substantially rectangular and has an inlet 13 in its front wall 14 at the lower portion thereof and adjacent the floor. The inlet 13 is preferably provided with louvres 15 or the like, and has a damper or closure member 16 mounted on a shaft 17 journaled in the end walls of the cabinet. One end of the shaft 17 which projects outside the cabinet, has an operating arm or lever 18 thereon cooperable with a toothed sector 18' or the like for holding the damper in adjusted open position and in tightly closed position, when desired. Within the cabinet 8 there is a compressor 19 which is driven by a motor 20, preferably electrical, which may be connected through a control switch, not shown, to a source of electric current. The compressor 19 may be of any of the well known forms or types for use in a mechanical refrigerating system. A condenser 21 is positioned within the cabinet in spaced relation to the front and rear walls thereof, and is preferably supported above the compressor, as by mounting the same on the compressor casing, or a separate supporting structure may be employed, if desired. The condenser 21 is preferably of the finned tube type positioned within an open-ended casing 22 providing a substantially horizontal air flow passage therethrough in which the condenser is positioned. A

platform or supporting member 23 which projects from the bottom wall of the casing 22 on the inlet side of the condenser, serves to support an electric fan motor 24 having a horizontal armature shaft on which is fixed a fan or impeller 25. The fan 25 is preferably of the propeller type, and is framed in the circular aperture of a baffle plate 26 or the like. The outlet from the condenser and casing 22 opens into an outlet or discharge duct or conduit 27 which extends upwardly within the cabinet and opens through the top wall thereof. The conduit 27 is preferably sealed to the casing 22 so that all the air discharged from the cabinet must pass through the casing and flow over the condenser. The conduit 27 leads to the outside of the building and in the plane of the sill 28 of the window opening 4, the conduit is turned laterally and preferably at an angle to lie upon the sill 28. The outlet end portion of the conduit 27 which extends across the sill 28 terminates substantially in the plane of the window 6, the bottom cross frame member of the window preferably engaging the top wall of the conduit. The conduit at its outlet end preferably has lateral flanges 29 which close the open spaces at the sides of the conduit and beneath the window. The portion of the conduit which extends across the sill is preferably of telescopic construction, as clearly shown in Fig. 4, to permit the same to be adjusted to varying widths of sills. The outlet or discharge opening of the conduit is also preferably provided with louvres 30 or the like. The cabinet 8 is provided with an air inlet in the form of a conduit or duct 31 which extends through the wall of the building and opens into the rear of the cabinet adjacent its bottom. This inlet conduit 31 is preferably lined with sound deadening material 32 which may be of felt, cork, or any of the other known sound insulating materials, and is provided with louvres 33 at its inlet end. Flow through this conduit 31 is controlled by a damper or closure member 34 supported and fixed on a shaft 35 supported in the conduit adjacent its communication with the cabinet. The damper 34 is controlled and operated by an arm or lever 36 fixed to the shaft 35 to which a link 37 is pivotally connected. The other end of link 37 is pivoted to an arm or lever 38 rigid with an operating shaft 39 which projects through the end wall of the cabinet. On the projecting end of shaft 39 there is an operating crank or lever arm 40 which is cooperable with a toothed sector or the like 41 fixed to the outside of the cabinet end wall. The foregoing operating mechanism for the damper 34 is merely one form which may be employed, it being obvious that other operating mechanism may be used. The cabinet 8 is sealed, except for the above described inlets and outlet, and is preferably lined with sound deadening or insulating material, designated 42, the damper 16 also preferably having an internal facing or backing 43 of such material. The sound insulating material in the conduit and cabinet serves to substantially eliminate the transmission of noise through the conduit into the building or room, and also overcomes transmission of vibration and noise from the motors, fan and compressor to the room.

The cabinet shown in Figs. 1, 3, 5 and 6 is substantially like that of Fig. 4, and therefore the primes of reference characters applied to Fig. 4 will designate like parts in Figs. 5 and 6. The compressor 19' is connected by a pipe or conduit 44 to the condenser 21'. From the condenser a pipe or conduit 45 leads to the cooling unit or element 12, from which a return pipe or conduit 46 leads to the inlet of the compressor. The cabinet has an inlet duct or conduit 47 and an outlet duct or conduit 48 which lie side by side and are preferably divided by a vertical septum or partition 49. The upper ends of the conduits 47, 48 which project through the top wall of the cabinet have laterally extending portions 50 which are adapted to lie upon the window sill 28, the partition 49 extending to the open ends of the portions 50. Each conduit is provided with a hollow extension 51 which fits telescopically within its conduit to provide for sills of different widths. The adjacent sides of the extensions are joined and sealed together at their outer ends by a vertical spacer member, and also have at their outer ends laterally outward extending vertical flanges or partitions 52. The outer ends of the extensions 51 and the flanges 52 fit in the window opening and receive the bottom edge of the window so as to seal the window opening against direct flow of air from and to the room. The inlet conduit 47 is provided with a damper or closure member 53 which is supported on an operating shaft 54 journaled in the partition 49 and an end wall of the casing through which it projects. The projecting end of shaft 54 has an operating lever or crank 55 cooperable with a locking sector 56 to hold the damper in adjusted position. The inlet conduit 47 within the casing has a substantially horizontal portion 57 which extends over the condenser 21' and has a downward open discharge end 58 between the front wall of the cabinet and the condenser fan for supplying air from outside the building directly to the fan inlet. The outlet duct or conduit 48 which extends downward into the cabinet beside the conduit 47, projects below the conduit 47 and is connected and sealed to the condenser casing, so that all the air discharged from the cabinet must pass through the condenser casing and over the condenser. The previously mentioned fresh air section of the cabinet 7 includes a fan 9' which may be exactly like the fan 9 of the cooling section. The fans 9 and 9' are mounted on the opposite ends of the shaft of a common fan motor 9''. The discharge conduit 59 of the fan 9' delivers air into the room through an outlet opening 11' in the top wall of the cabinet 7 which may be similar to, and is in end to end relation with the outlet 11 of the cooling section. The fan 9' may draw fresh outside air through an air inlet conduit 60 which, as shown, is similar to the outlet end portion of the previously mentioned conduit 27 of the cabinet 7, and extends over the sill of the window 5 into communication with the outside air through that window exactly as the outlet end portion of the conduit 27 extends over the sill of the window 6 into communication with the outside air through the last mentioned window. The air inlet conduit 60 extends over the top of the cabinet 7 above the cooling section 65 as well as above the fresh air section of the latter, but communicates only with the fresh air section, communication between the conduit 60 and the cooling section being prevented by a curved baffle wall 61. The fan 9' also draws room air into the fresh air section of the cabinet through the portion of the cabinet inlet opening 10 in front of said section. By means of a damper 62 in the air inlet conduit 60, the supply of fresh air to the fresh air section of the cabinet 70

7 may be shut off entirely or be regulated as conditions make desirable.

The operation of my apparatus in the form including the apparatus shown in Fig. 4 is as follows: When the refrigerating system is in operation to cool the air discharged from the cabinet 1, the inlet damper 16 is closed and the inlet damper 34 is open. The condenser cooling fan 25 driven by the motor 24 will draw air into the cabinet 8 from outside the building through the silenced duct or conduit 31. The air so drawn into the cabinet will be discharged by the fan through the condenser casing 22 and through the finned condenser 21. The warm air leaving the condenser will pass into the discharge conduit 27 and be led thereby from the cabinet and through the window opening 4 where the used and heated air will be discharged to atmosphere outside of the building. The cooled and condensed refrigerant will be circulated through the cooling unit or element by the pipes 45 and 46 and will be heated by the air discharged from the fan or blower 9 in its passage to the cabinet outlet 11, whence the cooled air will be discharged into the room to cool the same. In the winter, or at such other times as the refrigerating system is not in operation, or whenever desirable, the damper 34 may be closed and the damper 16 opened, so that the fan 25 will act to discharge air from the room through the duct 27 to the outside of the building.

The operation of the construction including the apparatus shown in Figs. 5 and 6 is substantially the same as that including the apparatus of Fig. 4. With the damper 16 closed and the damper 53 open, as shown, the fan 25 will draw air into the cabinet through the window opening via conduit 41, which indrawn air will be discharged by the downturned conduit outlet 58 at the fan inlet. The indrawn air will be discharged by the fan through the condenser casing 22 and into intimate heat absorbing relation to the condenser 21 to cool the condenser. The warmed air leaving the condenser will enter the outlet duct 48 to which the condenser casing is sealed, and will be led thereby upwardly out of the cabinet and then laterally by the outlet extension 51 through the window opening to the outside of the building. This form may also be employed for discharging air from the room by opening the damper 16 and closing the damper 53. Although I have shown a condenser, compressor, expander refrigerating system, it is to be understood that any other system of refrigeration or cooling employing a condenser may be used with equal facility in my apparatus.

It is to be noted that my apparatus provides for air cooling a condenser by outside air so that the room is not heated up by the air leaving the condenser, and that an efficient cooling system for the condenser is disclosed in which a forced draft of fresh or used cool air is utilized.

It is also to be noted that I have provided an efficient air cooling system for a room or compartment in which all of the apparatus is installed in the room to be cooled, so that the condenser cooling means may also be employed for discharging vitiated air from the room. The location of the apparatus partly in one and partly in another of two cabinets disposed in the described relation with two windows of the room, makes it possible to locate all of the apparatus required for ventilating and cooling a room within the latter, without objectionable reduction in the room space required for other purposes, and

without making the room unsightly, and without appreciable impairment of the capacity of the room occupants to see external objects through the windows, or of the light transmitting capacity of the windows. With the apparatus enclosed partly in one cabinet and partly in another, each cabinet may be generally similar in its spatial requirements and appearance to an ordinary enclosed radiator located in the customary manner immediately beneath and in front of a window. The establishment of communication with the outside air necessary for the introduction into the room of fresh air and for the discharge of vitiated room air and air used in cooling the refrigerating machinery partly, through the conduit extension of one and partly through the conduit extension of the other of the two cabinets, makes it possible to form the two conduit extensions of ample aggregate cross-section without requiring either to extend more than a few inches above the corresponding window sill.

What I claim and desire to secure by Letters Patent of the United States is:

1. An apparatus of the character described, comprising a cabinet adapted to be positioned in a room of a building and having an inlet from the room and an inlet from outside the building, a damper controlling the room inlet, said cabinet having an outlet discharging to the outside of the building, a refrigerant condenser in said cabinet, and a fan in said cabinet operable to draw air through one of said inlets and discharge the indrawn air over said condenser and through said outlet.

2. The combination with the wall of a room having two side by side window openings therein, of means for ventilating said room and conditioning the air therein comprising two cabinets resting on the room floor one adjacent each window and each having a conduit portion extending over the sill of the adjacent window and establishing communication through the window between the external air and the cabinet interior, apparatus in one cabinet comprising air moving means and a cooling device for supplying external air to the room and for recirculating and cooling room air, and refrigerating machinery in the other cabinet supplying cooling fluid to said cooling device and including a condenser, and means for moving external air into the cabinet and over the condenser and returning it to the external atmosphere.

3. Apparatus for ventilating and cooling the air in a room having two windows in its outer wall comprising two cabinets adapted for placement on the room floor, one beneath each window and each having a conduit projection at its upper end extending across the sill of the corresponding window and connecting the interior of the cabinet to the external air, refrigerating machinery including a motor driven compressor, a fan, and an air-cooled condenser in one of said cabinets, a cooling element and a motor driven fan in the other of said cabinets, and conduit connections between the cooling element and refrigeration machinery for the circulation of a cooling fluid through said cooling element.

4. In apparatus for ventilating and cooling the air in a room having two windows in its outer wall, the combination of means for ventilating said room and conditioning the air therein comprising two cabinets resting on the room floor one adjacent and beneath each window and each having a conduit projection extending over the sill of the adjacent window and establishing com-

5 munication between the external air and the cabinet interior, apparatus in one cabinet comprising air moving means and a cooling element for supplying external air to the room and for re-circulating and cooling room air, and refrigerating machinery in the other cabinet supplying

cooling fluid to said cooling device and including a condenser, and means for moving machinery cooling air through the last mentioned cabinet and out of the latter through its said conduit projection.

ALLSTON SARGENT.
